SWINGABLE SASH WINDOW

Andrew A. Ward, Berkeley, Calif.

Application March 14, 1932. Serial No. 598,536

10 Claims. (Cl. 20—57)

This invention relates to double sash windows and particularly to a manner of mounting such windows so that they may be readily washed on both sides from the interior of the building. Such 5 windows are shown for instance in my Patent No. 1,687,116, dated October 9, 1928, but these windows were of the reversible type and I found that it was somewhat difficult and awkward to manipulate the same, especially with large and 10 heavy windows. Also, this arrangement required a certain remodeling of the window casing structure.

The principal object of my present invention is to provide a structure arranged to be partly 15 mounted in permanent connection with the sash window and partly formed as a removable attachment whereby sash windows of any size may be temporarily transformed to the casement type of window, so that they may be swung inwardly of 20 the building to facilitate washing and like operations. The weight of sash windows, as is well known, is counter-balanced by weights and another object of my invention is to arrange the structure so that the weights may be utilized to 25 help support the windows when they are temporarily changed to the casement type. This is of especial advantage in large windows in which their weight would otherwise tend to make them sag and tear away from their connections when 30 swung inwardly.

Another object is to provide a structure for the purpose arranged to be easily applied either to new construction or on windows already in place.

These objects I accomplish by means of such 35 structure and relative arrangement of parts as will fully appear by a perusal of the following specification and claims.

In the drawings similar characters of reference indicate corresponding parts in the several views: 40 Fig. 1 is an interior elevation of a double sash window structure foreshortened and with the windows ready to be initially swung inwardly.

Fig. 2 is a top plan view of the structure showing the inner sash swung inwardly and with the 45 upper pivot clamp and fittings removed.

Fig. 3 is a fragmentary top plan view of the sashes in their closed position and mounted on the lower pivot clamp.

Fig. 4 is a similar view showing both sashes 50 swung inwardly.

Fig. 5 is an end view partly in section of the upper clamp.

Fig. 6 is a face view of a slotted plate for locating and supporting the upper clamp as mounted 55 in place on the window casing.

Fig. 7 is a fragmentary longitudinal section of a sash showing the connection of the block and tackle hook therewith.

Fig. 8 is a fragmentary view of the sash showing the upper pivot member arranged as a permanent element. 60

Fig. 9 is a fragmentary perspective view of the sash showing this pivot member as a detachable element.

Fig. 10 is a longitudinal section of said element 65 and the adjacent portion of the sash.

Fig. 11 is a fragmentary side view of the lower corner of the outer sash showing the lower pivot member attached thereto.

Fig. 12 is a similar view of the inner sash showing the corresponding pivot member. 70

Fig. 13 is a vertical section on the line 13—13 of Fig. 12.

Fig. 14 is a fragmentary sectional view showing the detachable connection means between the 75 inner stop and the window casing.

Fig. 15 is a fragmentary perspective of the intermediate stop bead showing the releasable holding element for the upper end of the removable portion of said stop. 80

Fig. 16 is a fragmentary vertical section of a sash showing the detachable connection means between the weight cord and the sash. 85

Fig. 17 is a similar view in perspective.

Referring now more particularly to the characters of reference on the drawings, the numeral 1 denotes in general the casing for the double sash inner and outer windows 2 and 3. The windows are spaced apart transversely of the casing and said casing is provided with guide beads 90

4 between the windows partially counter-sunk in the casing and with inner beads 5 bearing flatly against the casing. The lower portion 4a of the right hand intermediate bead, for a length greater than the height of the sashes, is removable. It is held in place at its lower end by its usual socketed fit in the casing and at its upper end by a swing clamp 6 pivoted on the fixed bead above, as shown in Fig. 15. 95

Similarly, the lower portions 5a of both the inner stops are removable from their upper portions and from the casing. They are removably secured in place by hand screws 7 turnably mounted on plates 8 secured to the stops and projecting through the same for engagement with tapped 100 sockets 9 driven into the casing, as shown in Fig.

14. Removal of these stop portions enables the windows to be moved inwardly when both sashes are lowered to the same level, as will be evident. 105

The cords 10 of the usual counter-weights 11 on 110

the right hand side of the sashes are provided on their free ends with enlarged heads 12. Each head has detachable engagement with a slotted socket member 13 set in the corresponding sash frame at the bottom of the cord groove 14 in the edge of said frame, as shown in Figs. 16 and 17.

The outer sash 3 has horns 15 depending from its lower corners as usual and these are cut off as necessary as indicated in Fig. 11 so that the bottom of the horns is on a level with the bottom of the inner sash when the tops of the sashes are on a common level. To the bottom of the left hand horn a plate 16 is securely attached, from which a pivot pin 17 depends, as shown in Fig. 11; this pin being as near the inner and left hand edges of the window as possible.

In the lower left hand corner of the inner sash 2 is mounted a vertical socket 18 also close to the left hand and inner edges of the sash. A pin 19 is slideable in this socket, being connected to a clamping screw 20 whose head rides in a vertical slot in the socket and which is exposed to the inner face of the sash, as shown in Figs. 12 and 13. This pin is arranged so that when in its lowest position it depends to the same level as the pin 17; and when raised to its limit it will just clear the bottom of the sash. The clamping screw 20 or any other equivalent device enables the pin to be rigidly held in either position.

On the upper edge of each sash frame at the left hand corner is fastened a plate 21 from which a pivot pin 22 projects upwardly in vertical alignment with the corresponding lower pin. Fig. 8 shows a permanent installation. If a detachable installation is desired the plates 21a having the upstanding pins 22a thereon are removable; each plate being seated on the top of the sash and located in place by side and end flanges 23. The plate is removably secured in place by a hand screw 24 mounted on a yieldable strip 25 secured to the plate; said screw being adapted to engage a tapped socket 26 sunk in the top of the sash. This arrangement is shown in Figs. 9 and 10. The presence of these pins whether detachable or permanent does not interfere with the opening or closing of the windows in the usual way. Their purpose is to serve as pivots for the windows about which the latter may swing inwardly, when said pivots are supported as follows:

Adapted to rest on the window sill and to straddle and be detachably secured to the adjacent vertical portion of the window casing is a C clamp 27 having a pair of blocks 28 mounted on its upper surface for separate transverse adjustment, to serve for different thickness of sashes. The upper surface of the blocks is provided with slots 29 and 30 in which the lower pins 19 and 17 respectively of the inner and outer sash ride. The slot 29 extends transversely of the window in an inward direction and is arranged so that the inner sash when swung inwardly and with the pin at the inner end of the slot, offers no interference with the full inward swinging movement of the outer sash, as shown in Fig. 4. The slot 30 is arranged so that the outer sash may be swung inwardly, when its pivot pin is moved along the slot, without interfering with the adjacent intermediate bead 4 or with the outer weather strip 31 on the casing.

The inner ends of both slots are provided with short reverse bends B to receive the pivot pins and hold them against an undesired tendency to return to their normal positions at the opposite ends of the slots.

Adapted to be disposed above the sashes and to be clamped against the casing is a similar C clamp 32 having slotted blocks 33 adjustably mounted on its under surface to receive the upper pins; the slots being of course the same length and having the same slope as those of the lower clamp. To support this clamp in a definite horizontal position an upstanding bar 32a is provided as an integral part of said clamp. A pair of transversely spaced circumferentially grooved pins 34 project toward the window casing from the bar. Said pins are adapted to enter vertical keyhole slots 35 provided in a plate 36 secured to the casing and extending under the intermediate bead 4 on both sides of the same, as shown in Fig. 6. The plate slots are arranged so that their large ends are uppermost and receive the heads of the pins, the lower narrow portions of the slots engaging in the pin grooves, as shown in Fig. 5. When the pins are at the bottom of the slots the clamp blocks 33 are supported at the proper level to engage the upper sash pins.

In operation the removable stop portions are first withdrawn. The lower clamp 27 is then mounted in position under the sash and said sashes are then lowered so as to cause the bottom pins to depend into the corresponding slots in the clamp blocks. The blocks are initially adjusted if necessary so that their spacing corresponds to the transverse spacing of the sashes. Independently the transverse alignment of the clamp as a whole may be assured by the fact that the outer clamping screw 27a of the clamp is only used to make an initial adjustment in the position of the clamp; while the inner clamping screw 27b is relied on in securing the clamp in place.

The sashes having both been lowered as far as possible, the upper clamp is placed in position and engaged with the upper sash pins; any necessary adjustments of the clamp or its blocks being of course first carried out just as was the case with the lower clamp. The sashes are then separately swung inwardly a short distance so as to expose the cord connecting members in the edges of the sashes and allow the cords to be disengaged. The sashes may then be swung the remaining distance, an inward pull being exerted at the same time so as to cause the pins to travel along the slots until they engage the reverse bends B. The outer surfaces of the windows are then exposed to the interior of the building and are conveniently positioned for washing.

If the windows are large and heavy I utilize the counter-weights to aid in supporting the weight of the windows in the following manner:

Swivelly connected to the bar 32a are the end blocks 37 of a pair of block and tackle units. The other end blocks are provided with hooks 38 adapted to engage slotted plates 39 secured on top of the sash frames over recesses 40 cut therein, as shown in Fig. 7, intermediate the right and left hand sides of the sashes. The free ends of the cables 41 of the block and tackles are provided with hooks 42 adapted to detachably engage with the heads 12 of the counter-weight cords, as indicated in dotted lines in Fig. 1, when such heads are disengaged from the windows as previously stated. The weights thus act on the block and tackles to draw the blocks together and thus yieldably support the sashes in the horizontal position as swung inwardly, without the cords extending directly from their top pulleys to the sashes and which would cause a severe binding, besides being in the way.

To prevent possible accident the clamps are tied together by a chain or flexible cord 43. The weight of the upper clamp acts as an anchor for the lower clamp while the latter is being applied 5 and in case it should slip out of the window, and vice versa.

While each sash preferably has a complete set of pivot pins of its own, one pair of clamps will serve for all the windows of the same size in a 10 single building and can be adjusted for all the sizes, while one adjustment of such clamps will of course serve for all the windows of a given size.

From the foregoing description it will be readily seen that I have produced such a device as 15 substantially fulfills the objects of the invention as set forth herein.

While this specification sets forth in detail the present and preferred construction of the device, still in practice such deviations from such 20 detail may be resorted to as do not form a departure from the spirit of the invention, as defined by the appended claims.

Having thus described my invention what I 25 claim as new and useful and desire to secure by Letters Patent is:

1. In combination with a sash window, aligned pins projecting vertically from the top and bottom of the sash adjacent one side edge thereof, clamps for removable attachment to the window 30 casing above and below the sash, and blocks mounted on the clamps for transverse adjustment and having recesses to receive the pins in turning relation.

2. In combination with a sash window, aligned 35 pins projecting vertically from the top and bottom of the sash adjacent one side edge thereof, clamps for removable attachment to the window casing above and below the sash, and blocks mounted on the clamps having slots 40 in which the corresponding pins turnably project; the slots extending transversely of the window in the direction of the inner face of the window from an inception positioned to engage the pins when the window is closed.

3. In combination with a sash window, aligned 45 pins projecting vertically from the top and bottom of the sash adjacent one side edge thereof, clamps for removable attachment to the window casing above and below the sash, and blocks 50 mounted on the clamps, said blocks having slots in which the corresponding pins turnably project; the slots extending transversely of the window in the direction of the inner face of the window from an inception positioned to engage the pins when the window is closed, and provided at their 55 inner terminations with a reverse bend into which the pins may be moved when the sash is swung inwardly from its closed position.

4. In combination with a counter-weighted 60 sash window having a detachable connection with the corresponding counter-weight cord on one side edge, means for hingedly mounting the sash along its opposite side edge in connection with the window casing for inward swinging 65 movement, and means to reapply the counter-weight when its cord is detached from the sash so that said counter-weight will aid in supporting the weight of the sash when thus swung.

5. In combination with a counter-weighted 70 sash window having a detachable connection with the corresponding counter-weight cord on one side edge, means for hingedly mounting the sash along its opposite side edge in connection with the window casing for inward swinging movement, a block and tackle unit one block of which

is mounted in connection with the hinge means above the sash, means to detachably connect the other block of the unit to the top of the sash, and means to detachably connect the free end of the tackle to the disconnected end of the 80 counter-weight cord.

6. In combination with inner and outer sash windows, removable guide beads on the window casing between the sash and inwardly of the inner sash, aligned pins projecting vertically from the top and bottom of both sashes adjacent one side edge thereof, clamps adapted to be removably attached to the casing above and below the 85 sashes on the same side as the pins and when said sashes are disposed at a common level, and separate transversely adjustable blocks mounted on said clamps and having recesses into which the separate sets of pins turnably project.

7. In combination with a sash window, aligned pins projecting vertically from the top and bottom of the sash adjacent one side edge thereof, clamps for removable attachment to the window 90 casing above and below the sash, and blocks mounted on the clamps having recesses to receive the pins in turning relation, and means between the upper clamp and the casing to locate and support said clamp at a predetermined level, said means comprising a circumferentially grooved pin projecting from the clamp toward the adjacent side of the casing, and a plate mounted on the casing and having a vertical key-hole slot for engagement with the pin; the lower small portion of said slot engaging the pin-groove.

8. In combination with a counter-weighted sash window having a detachable connection with the counterweight cord on one side edge, means for hingedly mounting the sash along its opposite side edge and at the top and bottom in connection with the window casing for inward swinging movement, said means including a device 100 removably mounted on the casing above the sash and including an upstanding bar, a block and tackle unit one block of which is swivelly connected to said bar, means to detachably connect the other block of the unit to the top of the sash 105 away from said opposite side edge, and means to detachably connect the free end of the tackle to the disconnected end of the counter weight cord; the tackle extending from said free end to the upper block.

9. In combination with a counter-weighted sash window having a detachable connection with the counterweight cord on one side edge, means for hingedly mounting the sash along its opposite side edge and at the top and bottom in connection with the window casing for inward swinging movement, said means including C-clamps straddling the casing, each clamp having adjustable clamping screws at its opposite ends to engage the inner and outer faces of the casing.

10. In combination with a sash window, aligned pins projecting from the top and bottom of the sash adjacent one side edge thereof, devices detachably mounted in connection with the window casing above and below the sash and having recesses for engagement with the pins, and means removably mounting the upper pin in place, said means comprising a plate to rest on the sash and on which said pin is secured and provided with flanges depending and engaging the vertical surfaces of the sash, a tapped socket mounted in the sash under the plate, and a clamping screw turnably mounted on the plate in vertical alignment with the socket to engage the same.

ANDREW A. WARD.
